UNITED STATES PATENT OFFICE.

ARTHUR E. SMALL, OF CHICAGO, ILLINOIS, ASSIGNOR TO UNION METAL PRODUCTS COMPANY, OF CHICAGO, ILLINOIS, A CORPORATION OF DELAWARE.

POSITIONING DEVICE FOR RAILWAY-CAR COUPLERS.

Original application filed June 16, 1926, Serial No. 116,407. Divided and this application filed February 2, 1928. Serial No. 251,311.

This device relates to means for automatically positioning the coupler of a railway car by gravity.

Two railway cars are automatically coupled together by the movement of their respective couplers forcing the tails of the pivoted knuckles behind gravity locks. The couplers are mounted in the cars so as to permit a limited amount of lateral movement. Such limitation is necessary and essential because if the couplers were allowed to move too far to either side, the couplers of the two cars being coupled would pass each other and not couple, thereby defeating the object of the automatic coupler. The greater the lateral movement of a coupler the less side pressure on the striking casting when the cars are going around curves. This lateral pressure forces the wheel flanges against the rail causing considerable friction and wearing of the rails and wheels.

One of the objects of the invention is to increase the amount of permissible lateral movement of a coupler by providing automatic means for returning the couplers to the longitudinal center of the car or at least close enough thereto so that the automatic couplers will couple. This is what is termed the "coupling range".

It is very often necessary to couple cars on curves and frequently when the radius of the curve is very small, as is common around industrial plants, the couplers of the two cars will be so far out of alignment that they will not automatically couple. Another object of the invention is to automatically bring such couplers within coupling range. The outside rail of a curved track is raised above the inside rail and I provide means whereby the coupler is moved toward the inside of the curve by gravity. This automatic gravity means also returns the coupler to the longitudinal center of the car when the car moves from the curved to the straight part of the track.

In my device the lateral movement between the coupler and the carrier is eliminated, thus reducing friction and consequent wear on the parts. This is quite an item particularly in sandy countries because couplers are costly and the replacement of a coupler means keeping the car out of service.

Coupler positioning devices reduces the

number of broken knuckles and guard arms on couplers which members are frequently bent or broken when the couplers are not within coupling range. Such devices also reduce the number of accidents to trainmen as they are not required to go between the cars and position the coupler preparatory to coupling.

A common form of car coupler positioning device comprises a coupler carrier swingably suspended by links from some part of the car so that the objects and advantages mentioned above are obtained and my invention is an improvement upon such devices and consists in providing a shiftable bearing construction to increase the eccentricity of the weight of the coupler (and its associated parts) about its point of support, thus increasing the resultant forces tending to return the coupler to the longitudinal center of the car (or away therefrom when the car is tipped.)

In my device the coupler carrier is swingably suspended from any convenient part of the car by a link at each of its ends and is provided with means, such as lugs, to prevent lateral movement of the coupler relative thereto. These links have a rolling engagement with the supporting car part and the carrier. The engaging surfaces are eccentric with each other so that upon lateral swing of the link, one of said surfaces rolls upon the other surface and gradually shifts the contacting or engaging line therebetween. The curved surfaces may be arcuate or of any desired contour.

The rolling bearing construction may be used on one or both links. It may be used to function on one link when the carrier moves in one direction and upon the other link when the carrier moves in the other direction, or it may be applied to one end of one link to function when the link swings in either direction.

In the drawings:
Fig. 1 shows a typical application of the device to a railway car.

Fig. 2 is a section on line 2-2 of Fig. 1.

Fig. 3 is a side elevation of Fig. 1.

Figs. 4 and 5 are skeleton diagrams showing the device respectively in normal position and with the carrier moved laterally.

Figs. 6, 7, 8 and 9 show various forms of

non-eccentric engaging surfaces between the link and a part of the car.

Figs. 10 and 11 show a specific form having certain advantages.

5 Figs. 12 and 13 show another specific form having certain advantages.

Figs. 1, 2 and 3 show a typical application of the device to a car. In this form the link 2 is pivoted to the carrier 3 by the trunnion 10 4, or any convenient manner. (See Figs. 6-7.) The striking casting (or other car part 5) has a flat surface 6 upon which the curved surface 7 of the link rolls. Figs. 4 and 5 show this adaptation (with the immaterial parts 15 of the car omitted) in normal and upon extreme lateral movement of the coupler 8.

The contacting engaging eccentric surfaces 10-11 of the link and car part, respectively, may both be curved downwardly, as shown 20 in Fig. 6, or both surfaces 12-13 may be curved upwardly, as shown in Fig. 9. The engaging surface 14 of the car part may be curved and the engaging surfaces 15 of the link may be flat, as shown in Fig. 7, or vice 25 versa, as shown in Fig. 8. In any of the above the engaging surfaces must be non-concentric. When a rolling engagement is used at both ends of the link it is not necessary to make them of the same type (as 30 shown in Fig. 12.) In fact, if the opposite ends of the link are made of opposite types (as shown in Fig. 10) the link could be made symmetrical about its horizontal center which would assure proper assemblage of the device 35 on the car.

It is desirable to provide some means to prevent slippage between the engaging surfaces, thus forcing one surface to roll upon the other, thereby maintaining operative 40 relation between the parts of the device. This may be accomplished by a rack and tooth arrangement or by a single tooth 20 engaging a depression 21 in the other element (Fig. 10) or the link may be held in place resting between 45 oppositely disposed portions 22-23 of the car part (or carrier) as shown in Fig. 4.

In the usual centering device link, which is pivoted at both ends, the eccentricity of the 50 load upon the link is equal to the lateral swing "A" of the carrier, but in my arrangement this eccentricity is increased by the distance the link rolls upon the car part. In other words, when the carrier moves distance 55 "A" (Fig. 5) the eccentricity is distance "B", which is greater than "A".

As one surface rolls upon the other the effective radius of the link is changed and the parts may be so proportioned as to maintain the same radius, or to increase or decrease it, as desired. In any event the eccentricity of the load about its support is increased.

In the construction shown in Figs. 12 and 13 the link 25 has a rolling engagement with 65 both the car part 5 at its upper end and

with the carrier 3 at its lower end. The striking casting (or other part of the car) has an upwardly curved surface 26 over which the eccentric curved surface 27 of the link rolls when the link swings laterally. The link is also provided with an upwardly curved surface 28 over which the under eccentric curved surface 29 of the carrier rolls. The eccentricity of the load on the link is not only increased by the distance the upper part of the link rolls upon the car part, but also by the distance the carrier rolls upon the link, which eccentricity is shown as "C" in Fig. 5. It will be noted that the contacting line between the carrier and the link is further from the normal vertical center line of the link than it would be if a pivoted connection were used between the link and the carried. The engaging line between the link of the car part 5 is lowered by having an upwardly curved surface on the car part.

Fig. 10 shows an application wherein the car part 5 and carrier 3 each present an eccentric curved engaging surface (30-31) to the link and the engaging surfaces (32-33) of the link 34 are curved toward each other. A symmetrical link is thus obtained. Fig. 11 shows a detail of this link 34. The tooth 20 engages the notch 21 and maintains the desired relation between the parts.

The broad idea of shifting the bearings between the link and a car part and between the link and the carrier (either one or both) is covered by applications for patents, Serial No. 116,406, and Serial No. 116,408, filed June 16, 1926, which applications also claim certain details of construction.

The accompanying drawings illustrate the preferred form of the invention, though it is to be understood that the invention is not limited to the exact details of construction shown and described, as it is obvious that various modifications thereof within the scope of the claims will occur to persons skilled in the art.

This is a division of my co-pending application Serial No. 116,407, filed June 16, 1926.

I claim:

1. In a railway car; the combination of a car part element, a coupler carrier element, and a pair of links swingably suspending the opposite ends of the carrier thereto, eccentric engaging surfaces between one of said links and said elements, respectively, extending on both sides of the normal contacting lines between the respective parts whereby upon lateral swing of the links in either direction the engaging surfaces roll upon each other and gradually shift the contacting lines therebetween.

2. In a railway car; the combination of a car part element, a coupler carrier element, and a pair of links swingably suspending the opposite ends of the carrier thereto, one of said links provided with lateral extensions,

eccentric rolling engaging surfaces between said extensions and one of said elements, whereby upon lateral swing of the link the plane of contact between the link and its adjacent element is shifted.

3. In a railway car; the combination of a car part element, a coupler carrier element, and a pair of links swingably suspending the opposite ends of the carrier thereto, one of said links provided with lateral extensions, downwardly projecting eccentric rolling engaging surfaces between said extensions and one of said elements, whereby upon lateral swing of the link the place of contact be-

tween the link and its adjacent element is shifted.

4. In a railway car; the combination of a car part having a slot with downwardly projecting bearing surfaces on opposite sides thereof, a coupler carrier and a pair of links swingably suspending said carrier from said car part, one of said links having oppositely projecting trunnions at one end thereof, each trunnion having a downwardly projecting rolling surface eccentric from and engaging said bearing surfaces.

ARTHUR E. SMALL.
